UNITED STATES PATENT OFFICE

133,101

DESIGN FOR A SETTEE

Frank Mastrangelo, Fitchburg, Mass.

Application January 26, 1942, Serial No. 105,434

Term of patent 3½ years

To all whom it may concern:

Be it known that I, Frank Mastrangelo, a citizen of the United States, residing at Fitchburg, in the county of Worcester and State of Massachusetts, have invented a new, original, and ornamental Design for a Settee, of which the following is a specification, reference being had to the accompanying drawing, forming part thereof.

The figure is a perspective view of a settee, showing my new design.

The opposite end of the settee is plain and unornamented.

I claim:

The ornamental design for a settee, as shown and described.

FRANK MASTRANGELO.
